UNITED STATES PATENT OFFICE.

EDWARD WESTON, OF NEWARK, NEW JERSEY.

DESIGN FOR AN ELECTRICAL-INSTRUMENT CASE.

SPECIFICATION forming part of Design No. 28,395, dated March 22, 1898.

Application filed December 7, 1897. Serial No. 661,109. Term of patent 14 years.

all whom it may concern:

Be it known that I, EDWARD WESTON, a subject of Her Majesty the Queen of Great Britain, residing at Newark, in the county of Essex, and State of New Jersey, have invented and produced a new and original Design for cases for Electrical Measuring Instruments, which the following is a specification, reference being had to the accompanying drawings, forming part thereof.

Figure 1 is a plan view of a case for electrical measuring instruments, showing my design; and Fig. 2 is a side elevational view thereof as seen looking at Fig. 1 from the bottom toward the top of the drawings.

The leading or characteristic feature of my design comprises an instrument case or body having a relatively rectangular form at each of its opposite ends, with an outwardly-curved

portion between said ends, as shown in the drawings, in which—

A represents the body part of the case; L and L', extensions near the bottom thereof; P and P', rectangular-shaped panels, and M and M' curvilinear panels on the top face of the body or case.

Having thus described my invention, what I claim as new, and desire to secure by Letters Patent, is—

The design for an electrical-instrument case as herein shown and described.

In testimony whereof I have hereunto subscribed my name this 2d day of December, 1897.

EDWARD WESTON.
